(57) **CLAIM**

The ornamental design for a light fixture with backbox, as shown and described.

DESCRIPTION

FIG. 1 is a top-side-rear perspective view of a light fixture with backbox, showing our new design;

FIG. 2 is a bottom-side-rear perspective view of the light fixture with backbox of FIG. 1;

FIG. 3 is a top plan view of the light fixture with backbox of FIG. 1;

FIG. 4 is a bottom plan view of the light fixture with backbox of FIG. 1;

FIG. 5 is a front elevation view of the light fixture with backbox of FIG. 1;

FIG. 6 is a rear elevation view of the light fixture with backbox of FIG. 1;

FIG. 7 is a left-side elevation view of the light fixture with backbox of FIG. 1; and,

FIG. 8 is a right-side elevation view of the light fixture with backbox of FIG. 1.

The broken lines shown in the figures represent unclaimed subject matter and form no part of the claimed design.
